(57) **CLAIM**

The ornamental design for a talking T-shirt with recording module, as shown and described.

DESCRIPTION

FIG. 1 is a perspective view of the combined T-shirt with recording module showing my new design.

FIG. 2 is a back view thereof.

FIG. 3 is an interior view of the T-shirt showing the module being placed inside the waterproof receptacle.

FIG. 4 is a right side interior view of the T-shirt showing the module being placed inside the waterproof receptacle.

FIG. 5 is a right side interior view of the T-shirt showing the module being placed inside the waterproof receptacle.

FIG. 6 is a left side interior view of the T-shirt showing the module being placed inside the waterproof receptacle.

FIG. 7 is a left side interior view of the T-shirt showing the module being placed inside the waterproof receptacle.

FIG. 8 is a perspective view of the interior of the T-shirt and further showing a front perspective view of the module that has been removed from the waterproof receptacle.

FIG. 9 is a perspective view of the interior of the T-shirt and further showing a back view of the module that has been removed from the waterproof receptacle.

FIG. 10 is a perspective view of the interior of the T-shirt and further showing a left side view of the module that has been removed from the waterproof receptacle.

FIG. 11 is a perspective view of the interior of the T-shirt and further showing a left side view of the module that has been removed from the waterproof receptacle.

FIG. 12 is a perspective view of the interior of the T-shirt and further showing a right side view of the module that has been removed from the water proof receptacle.

FIG. 13 is a perspective view of the interior of the T-shirt and further showing a right side view of the module that has been removed from the water proof receptacle.

FIG. 14 is a perspective view of the interior of the T-shirt and further showing a bottom view of the module that has been removed from the waterproof receptacle.

(Continued)

FIG. 15 is a perspective view of the interior of the T-shirt and further showing a back perspective view of the module that has been removed from the waterproof receptacle.

FIG. 16 is an enlarged view of the module of FIG. 3 being placed inside the waterproof receptacle.

FIG. 17 is an enlarged view of the module of FIG. 4 being placed inside the waterproof receptacle.

FIG. 18 is an enlarged view of the module of FIG. 5 being placed inside the waterproof receptacle.

FIG. 19 is an enlarged view of the module of FIG. 6 being placed inside the waterproof receptacle.

FIG. 20 is an enlarged view of the module of FIG. 7 being placed inside the waterproof receptacle.

FIG. 21 is an enlarged view showing the front perspective view of the module of FIG. 8 that has been removed from the waterproof receptacle.

FIG. 22 is an enlarged view showing the back view of the module of FIG. 9 that has been removed from the waterproof receptacle.

FIG. 23 is an enlarged view showing the left side view of the module of FIG. 10 that has been removed from the waterproof receptacle.

FIG. 24 is an enlarged view further showing a left side view of the module of FIG. 11 that has been removed from the waterproof receptacle.

FIG. 25 is an enlarged view showing the right side view of the module of FIG. 12 that has been removed from the waterproof receptacle.

FIG. 26 is an enlarged view further showing the right side view of the module of FIG. 13 that has been removed from the waterproof receptacle.

FIG. 27 is an enlarged view further showing the bottom view of the module of FIG. 14 that has been removed from the waterproof receptacle; and,

FIG. 28 is an enlarged view further showing the back perspective view of the module of FIG. 15 that has been removed from the waterproof receptacle.

The broken lines shown in FIG. 1 on the front side of the T-shirt form no part of the claimed design.

The broken lines enclosing the modules shown in FIGS. 3-15 form no part of the claimed design.

The broken lines enclosing the enlarged modules shown in FIGS. 16-28 form no part of the claimed design.

1 Claim, 28 Drawing Sheets
